D. W. VAN TINE

ELECTRIC HEATER FOR CURLING IRONS

Filed June 3, 1925

INVENTOR:
David W. Van Tine.
BY
Wiedersheim Fairbanks.
ATTORNEYS.

UNITED STATES PATENT OFFICE.

DAVID W. VAN TINE, OF PHILADELPHIA, PENNSYLVANIA.

ELECTRIC HEATER FOR CURLING IRONS.

Application filed June 3, 1925. Serial No. 34,507.

To all whom it may concern:

Be known that I, DAVID W. VAN TINE, a citizen of the United States, residing at Philadelphia, in the county of Philadelphia 5 and State of Pennsylvania, have invented a certain new and useful Electric Heater for Curling Irons, of which the following is a specification.

My invention relates to a novel construction of electric heaters for curling irons, wherein I employ an outer casing which contains a central core of insulating material around which the resistance coils of the electric heating elements are wound, the 15 space between said core and said casing being filled with suitable non-conducting material of such a character that when an electric circuit is closed the latent heat within the casing will keep the heater hot for a 20 considerable period of time.

It further consists of a novel construction of heater casing and end supports having oppositely disposed laterally extending arms which serve as supports for curling irons 25 at the will of the user.

It further consists of a novel construction of a hollow, central insulating core having a shoulder which abuts against the front end closure of the heater casing, 30 whereby a finished appearance is given to the device and whereby the latter can be readily assembled, thereby cheapening the process of manufacture.

For the purpose of illustrating my invention I have shown in the accompanying drawings two forms thereof which are at present preferred by me, since the same have been found in practice to give satisfactory and reliable results, although it is 35 to be understood that the various instrumentalities of which my invention consists can be variously arranged and organized and that my invention is not limited to the precise arrangement and organization of the 40 instrumentalities as herein shown and described.

Fig. 1, represents a perspective view of an electric heater for curling irons embodying my invention.

Fig. 2, represents a longitudinal section on line 2—2 of Fig. 1.

Fig. 3, represents a transverse section on line 3—3 of Fig. 2; and

Fig. 4, represents a perspective view of a 55 slightly modified form of curling iron support.

Referring to the drawings, in which like reference characters indicate like parts, 1 designates my novel construction of a curling iron, the same comprising a casing 2, 60 within which is located the centrally disposed core, 3, open at both ends, and which is provided at its front with a beveled end 4 and having the rear shoulder 5 which abuts against the closure or cap 6, which 65 cap is provided with a rearwardly extending flange 7. 8 designates an encircling ring which surrounds the flange 7 and is provided with a vertical lower member which terminates in the feet 10, which are 70 secured to a suitable base 11 by the screws or other fastening devices 12. 13 designates horizontally or laterally projecting arms which have the outer vertical terminals 14, 75 said arms being provided with the downwardly extending flanges 15, which are secured in position by the bolts 16, the latter passing through the members 15 and 9, as will be understood from Fig. 3. 17 designates the electric heating or resistance coil, 80 which preferably enters the rear wall 18 of the heater and which is so constructed, in proportion to the bore or chamber 19 of the core 3, that said bore or chamber will be effectively heated to the desired degree 85 under all conditions. The space between the core 3 and the casing 2 is filled with suitable non-conducting material as indicated at 20, which retains latent heat from 90 the heating coil so that when the electric circuit is open the device will function for a long period of time as a heater. Thus only a minimum quantity of electricity is required.

In the construction seen in Fig. 4, I have 95 shown a preferred form of end closures 21 wherein 22 designates the disc or closure member having the central hole 23 therein, through which the core 3 is inserted. 24 designates the horizontally or laterally extending arms and 25 the foot whereby the device is supported upon and secured to the base 11. 26 designates a rearwardly extending flange which is adapted to receive the ends of the heater casing 2. The 100 construction seen in Fig. 4 is substantially the same as that disclosed in Fig. 3 except that, being a unitary structure, it can be more readily assembled upon or disconnected from the ends of the casing 2, said 105 ends fitting nicely within the flange 25 as is evident. By constructing the heater with 110

the end closures 21, as seen in Fig. 4, it is apparent that the number of parts is reduced to a minimum, since, aside from the heating coil, it is only necessary to employ 5 the core 3, the casing 2 and the end closures 21, which parts, when assembled, will function efficiently as a heater for curling irons or other purposes. The provision of the arms 13 or 24 affords a convenient support 10 for the heated curling irons, while they are temporarily not in use. The provision of the beveled end 4, and the shoulder 5 enables the core 3 to be readily and quickly inserted in position as is evident.

15 Having thus described my invention, what I claim as new and desire to secure by Letters Patent, is:

1. A device of the character stated comprising a casing member, flanged caps for 20 closing both ends thereof said caps fitting over said casing member, a tubular member arranged within said casing member and projected through one end thereof to receive an article to be heated, a heating coil surrounding said tubular member, a base, means carried by said base to support the caps of said casing member and laterally disposed rests at each end and upon both sides of the device and rigidly clamped 25 directly to said base for supporting articles to be heated.

2. A device of the character stated comprising a casing member, flanged caps for closing both ends thereof said caps fitting

over said casing member, a tubular member arranged within said member and projected through one end thereof to receive an article to be heated, the projected end of said tubular member being tapered and having an exterior shoulder which abuts 40 against an adjacent cap exterior, a heating coil surrounding said tubular member, a base, means carried by said base to support the caps of said casing member and laterally disposed rests at each end and upon both sides of the device for supporting articles to be heated.

3. A device of the character stated comprising a cylindrical member, flanged caps for closing both ends thereof said caps fitting 50 over said casing member, a tubular member arranged within said cylindrical member and projected through one end thereof to receive an article to be heated, a heating coil surrounding said tubular member, a base, means including a right angle member formed integral with said caps and carried by said base to support the caps of said cylindrical member and laterally disposed rests including oppositely disposed, laterally extended, horizontal arms at each end and upon both sides of the device for supporting articles to be heated.

In testimony whereof, I have hereunto 55 signed my name.

DAVID W. VAN TINE.
